UNITED STATES PATENT OFFICE.

JOHN N. DERRICK AND MILLARD M. VANN, OF ROCKWOOD, TENNESSEE.

MINE-SHEAVE.

1,220,963.

Specification of Letters Patent. Patented Mar. 27, 1917.

Application filed December 22, 1916. Serial No. 138,476.

To all whom it may concern:

Be it known that we, JOHN N. DERRICK and MILLARD M. VANN, citizens of the United States, residing at Rockwood, in the 5 county of Roane and State of Tennessee, have invented new and useful Improvements in Mine-Sheaves, of which the following is a specification.

This invention relates to sheaves, especially adapted for use in connection with railway tracks in mines, or other places where haulage is on an incline.

The object of the present invention is to provide a sheave for use as above stated by 15 means of which the movement of cars operated by rope haulage is facilitated.

Another object of the invention is to provide a sheave that can be readily positioned in any mine track irrespective of the condition 20 of the ties, the supporting element of the sheave replacing the tie and acting as a gage bar for the rails.

A further object of the invention is the provision of a device of this class which 25 will combine the maximum of strength with the minimum cost of construction, consistent with its strength, and which will combine simplicity and long life, there being only one wearing part which may be easily and 30 cheaply replaced.

With the foregoing objects in view the invention consists of a combined gage and supporting bar adapted to be clamped to the base of the rails, a sheave mounted upon 35 a stationary vertical pin keyed to the said bar, a bearing arm bolted to the bar and supporting the upper end of the pin and a rope guiding element for directing the rope or cable into position.

40 In the drawings;—

Figure 1 is a side elevation of the device applied to a track; and

Fig. 2 is a top plan view of the same.

Ordinarily it is the practice to secure a 45 sheave for use in connection with rope haulage in mines, to a tie between the tracks. This tie may become worn or rotten, and it is often difficult to secure the sheave thereto in a manner to prevent its continual pulling out and a consequent loss of time and 50 annoyance caused thereby. The present in-

vention aims to overcome these difficulties, and to this end provides a combined gage and supporting bar 1 adapted to be placed transversely across the rails and secured to 55 their base flanges. To accomplish this one end of the bar is provided with an upturned rail engaging end 2, for engagement with one flange of a rail 3, the opposite flange of this rail being engaged by a removable 60 clamp 4 secured to the bar by a countersunk post 5 and a nut 6. The opposite end of the bar 1 is secured to one flange of the rail 7 by a removable clamp 8 similar to the clamp 4 just described. A combined clamp 65 and bearing arm 9 is secured to the bar by the countersunk bolts 10, one end of this arm having a clamping member 11 for engagement with the rail 7.

Keyed within an opening 12 formed in 70 the bar 1 is a vertical pin 13, the key being shown at 14. This pin supports a sheave 15, and at its upper end is provided with a head 16 countersunk into one end of the bearing arm 9 as shown at 17. Spacing 75 washers 18 are provided at each end of the sheave 15, upon the pin 13.

In order to readily guide the rope or cable into position within the flanges of the sheave, the bar 1 is formed with a guiding 80 element in the form of an inclined raised portion 19. This guiding element is shown in Fig. 1 as located in juxtaposition to the lower flange of the sheave 15, so that when the rope or cable is pulled over the surface 85 of the bar 11 it will be readily guided into position upon the sheave.

It will be seen from the foregoing description when taken in connection with the accompanying drawings that the invention 90 provides a simple and efficient sheave for use in connection with rope haulage through mines, and one that may be readily positioned at any point along the track irrespective of the condition of the ties. 95

Having described the invention, what is claimed is;

1. The combination with a track, of a bar secured thereto, a sheave supported upon said bar and an inclined guiding element 100 adjacent the lower end of said sheave.
2. The combination with a track, of a bar

secured thereto, a sheave supported upon said bar and a guiding element formed in said bar adjacent said sheave.

3. The combination with a track, of a bar secured thereto, clamps for said bar, a flanged pulley mounted upon a vertical pin keyed to said bar, a bearing arm secured to

the bar and supporting the upper end of the pin, and a guiding element formed upon said bar adjacent said sheave. 10

In testimony whereof we affix our signatures.

JOHN N. DERRICK.
MILLARD M. VANN.
